CLAIM

The ornamental design for a fitness apparatus, as shown and described.

DESCRIPTION

FIG. 1 is a top front right perspective view of a fitness apparatus in a first configuration, showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top front right perspective view of the fitness apparatus in a second configuration, showing my new design;

FIG. 9 is a front elevational view thereof;

FIG. 10 is a back elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a top front right perspective view of the fitness apparatus in a third configuration, showing my new design;

FIG. 16 is a front elevational view thereof;

FIG. 17 is a back elevational view thereof;

FIG. 18 is a left side elevational view thereof;

FIG. 19 is a right side elevational view thereof;

FIG. 20 is a top plan view thereof;

FIG. 21 is a bottom plan view thereof; and,

FIG. 22 is a right side elevational view of the fitness apparatus in the second configuration.

The directional arrows shown in broken lines indicate directions and ranges of movement of elements of the claimed design in operation, and form no part of the claimed design. In addition, the broken lines shown in the drawings represent portions of the fitness apparatus that form no part of the claimed design.
